SIEGMUND LOEWE, OF BERLIN, FRIEDENAU, GERMANY, ASSIGNOR TO RADIO CORPORATION OF AMERICA, A CORPORATION OF DELAWARE

MULTIPLE-UNIT TUBE

Application filed April 29, 1927, Serial No. 187,680, and in Germany July 19, 1926.

This invention relates to a vacuum tube, and more particularly to a multiple-unit tube.

Multiple-unit tubes in the sense as herein-after used are vacuum bulbs in which, within one and the same vacuous space, at least two amplifier systems belonging to different stages are arranged, each system comprising a filamentary, a grid or control electrode and a plate or anode, said systems being connected 10 inside the same vacuous space by coupling means such as resistances and capacities.

Multiple-unit tubes of this kind have heretofore been known only in the form of resistance-coupled amplifier tubes, in which 15 the coupling between the first plate and the second grid was effected by the aid of high-ohmic resistances with the intermediary of a transfer condenser. It has been found that such multiple-unit tubes result in a very high 20 aperiodic amplification, but that this, under certain circumstances, is associated with a drawback. Since the aperiodic amplification with approximately the same effectiveness extends over a relatively large frequency range 25 or band, it results that in the output circuit of such resistance-coupled multiple-unit systems very great amplifications are obtained, but at the same time also very little selectivity. But it is desirable to preserve the advantages offered by multiple-unit systems, 30 without having to accomplish amplification in a purely aperiodic manner as is predominantly true of capacity-resistance-coupled arrangements.

According to the disclosures of this invention, it is an object of this invention to provide ways and means whereby selectivity is rendered feasible in the rear of the first system, or, in cases where greater numbers of amplifier stages are dealt with, ahead of the 35 last system.

The invention shall be explained more fully by reference to the accompanying drawing.

Figure 1 shows a diagrammatic view of a 40 three-unit or three-stage tube of the design customary heretofore, and

Figure 2 diagrammatically shows a tube built according to my invention.

Inside a common vacuous space 1 is a three 45 stage amplifier system. The filamentary cath-

odes are denoted by 2, 3, 4; the grids or control electrodes by 5, 6, 7; the plates or anodes by 8, 9, 10. 11 and 12 in Fig. 1 are plate or anode resistances, 13 and 14 are grid leaks, and 15 and 16 are coupling, that is, transfer condensers.

Now, this form of arrangement of multiple-unit tubes does not permit selectivity. The potential variations supplied to the input lead 17 to grid 5 reappear in aperiodically amplified form in the consumer circuit connected with the plate 10. According to the present invention, such a multiple-unit tube is equipped in a way as shown, for example, in Figure 2 to allow of selectivity.

Although the coupling condenser 15 and the leak resistance 13 are enclosed inside the same vacuous space, in this embodiment, the first plate is separately brought out at 18. In this manner, it is possible to use any convenient element as the alternating current resistance for the plate circuit, for instance, a tuned circuit or a tickler coil (reaction coil), which in well-known manner is in regenerative coupling relationship with the 55 tuned input circuit connected with the grid lead 17 to grid 5, and which is brought to the joint plate battery. In this manner, to be sure, purely aperiodic amplification can be insured by inserting outside the tube a pure 60 ohmic resistance which is connected with the plate battery. But it is now feasible to influence and shape the frequency characteristic of the tube in any desired manner, more 65 particularly, to enhance selectivity by the 70 insertion of tuned circuits or by the provision of back-coupling. Instead of bringing out the first plate, this selectivity may, of course, be also effected with one of the higher stages 75 save the last. In the case of the last plate, 80 action as regards selectivity of the amplifier 85 device is not practically possible. According to whether the first, second, or third plate is brought out, the first or second, etc., plate resistance is to be omitted. In this manner, 90 the advantages of multiple-unit tubes are insured without the circuit advantages of separate tube systems having to be sacrificed.

I claim as my invention:

1. A multiple unit tube enclosing a plu- 100

rality of capacity-coupled amplification stages, each stage comprising an anode, a control electrode and a cathode, and an external lead directly connected to the anode of a stage preceding the last.

2. A multiple unit tube enclosing a plurality of capacity-coupled amplification stages, each stage comprising an anode, a control electrode and a cathode, and an external lead directly connected to the anode of the first stage.

3. A multiple unit tube enclosing a plurality of amplification stages, each stage comprising an anode, a control electrode and a cathode, the anode in a stage preceding the last stage having an external lead directly connected thereto, a resistance connected to the anode in the next succeeding stage, a coupling condenser connected between the anode of each stage and the control electrode of the next succeeding stage, and a leak resistance connected to the control electrode of each stage except the said preceding stage, said coupling condensers and resistances being enclosed within the tube.

4. A multi-stage thermionic amplifier, comprising the combination with an evacuated envelope, of several amplifier stages housed within said envelope, each stage comprising an anode, a control electrode and a cathode, an external lead directly connected to the anode of the first stage, an impedance connected to the anode of the next succeeding stage, a coupling condenser between the anode of each stage and the control electrode of the next stage, and an impedance connected to the control electrode of each stage except the first, said coupling condensers and impedances being enclosed within the envelope.

40 SIEGMUND LOEWE.
